UNITED STATES PATENT OFFICE.

STEPHEN SERA, OF MCKEESPORT, PENNSYLVANIA.

THREADING DIE.

Application filed April 17, 1924. Serial No. 707,163.

To all whom it may concern:

Be it known that I, STEPHEN SERA, a citizen of the United States of America, residing at McKeesport, in the county of Allegheny and State of Pennsylvania, have invented certain new and useful Improvements in Threading Dies, of which the following is a specification.

This invention relates to certain new and useful improvements in threading dies and has particular reference to the mounting and adjustability of the cutter bars or blades of the die block, the die being of the type for threading external threads upon an object.

The primary object of the invention is to provide a threading die and particular mechanism for adjusting the thread cutting blades thereof, adjusting screws associated with relatively movable sectional members comprising wedging devices cooperating with sliding pins that engage the rear edge of the thread cutters for varying the projection of the cutters within the central opening in the die block.

With the above and other objects in view as the nature of the invention is better understood, the same consists of the novel form, combination and arrangement of parts hereinafter more fully described, shown in the accompanying drawings and claimed.

In the drawings, wherein like reference characters designate corresponding parts throughout the several views,

Figure 1 is a top plan view of the threading die constructed in accordance with the present invention,

Figure 2 is a side elevational view of the same,

Figure 3 is a side elevational view of one section of the die,

Figure 4 is a cross-sectional view taken on line IV—IV of Fig. 1 showing the bolt for securing the face plate to the die block,

Figure 5 is a detail sectional view taken on the line V—V of Fig. 1 showing the adjustable mounting for one of the thread cutting blades, and

Figures 6 and 7 show side and edge elevational views of the screw-operated two-part wedge blocks for adjusting the thread cutting blades.

The threading die embodies a block formed of mating semi-circular sections 1 having registering semi-circular openings forming a central circular opening into

which thread cutting blades carried by the die block extend, the die block sections being assembled in any convenient manner. Face plates 2 are secured to the die block sections at the sides thereof facing the open sides of the pockets that house the thread cutter blades.

Each of the die block sections 1 is provided with a plurality of spaced tangentially disposed pockets 3 opening at the center of the block and also open at the side of the block adjacent the face plate 2 as shown in Fig. 5, a thread cutting plate 4 having a cutting edge 5 being adjustably mounted in each pocket 3 as illustrated. The face plate 2 is secured to its corresponding die block section by the bolts 7 as illustrated in Fig. 4.

The adjustable mounting for the thread cutting blades 4 include the provision of an opening 8 in the die block in the wall thereof aligned with the pocket 3, an opening 9 forming communication between the rear end of the pocket 3 and the opening 8 at a point spaced from the bottom wall 8^a of the opening 8 as shown in Fig. 5. A pin 10 projecting through the opening 9 and spaced from the side walls thereof, the pin being freely supported in the disk 11 and having the headed end 12 thereof disposed in the opening 8. A stud screw 13 is threaded through the side wall of the block section 1 aligned with the pin 10 with the head of the pin normally abutting the inner end thereof.

A screw-operated two-part wedge member extends into each pocket 8 for shifting the pin 10 in a direction toward the pocket 3 for projecting the thread cutting blade 4 into the central opening of the threading die, the outer face of the base plate 2 being provided with a relatively large socket 14 having a reduced opening 15 in the bottom wall thereof aligned with the opening 8 and through which opening 15 the threaded portion 16 of the rod 17 freely projects. The rod 17 is provided with a disk 18 at the outer end of the threaded portion 16 that is disposed within the pocket 14 and engages the gasket 19 interposed between the disk and the bottom wall of the pocket, the outer end of the rod 17 being provided with a wrench receiving end 20 for operation thereof. The two-part wedge member includes a head 21 having a threaded axial opening in the outer end thereof into which

the threaded end 16 of the rod is received, the head 21 carrying a reduced extension 22 having oppositely disposed outwardly directed shoulders 23 at the outer end thereof as clearly shown in Figs. 6 and 7. The wedging point 24 of the two-part wedge member is provided at the larger end thereof with oppositely positioned legs 25, the adjacent faces of which are cutaway at 10 their inner ends as at 26 providing a transverse opening 27, the legs 25 being received on the reduced portion 22 of the head 21 while the shoulders 23 are received in the opening 27 and engage the opposite side 15 walls of the cutaway portions 26 so that the wedge point 24 is permitted a pivotal and lateral sliding movement upon the reduced extension of the head as will be clearly evident from an inspection of Figs. 6 and 7. 20 After the thread cutting blade 4 has been adjusted tangentially of the die block, the same is retained in its adjusted position by the stud screw 28 threaded through the face plate 2 and engaging the faced strip 29 positioned against the adjacent side edge of the blade as shown in Fig. 5.

The block sections of the threading die being assembled as illustrated in Fig. 1, the same is suitably supported in a machine 30 by devices entering the openings 30 in the block and face plate sections and the thread cutting blades 4 are adjusted tangentially of the die block sections by the wedge members above described. The tapered ends of the 35 sections 24 of the two-part wedge members are forced between the stud screw 13 and the head 12 of the pin 10, the free mounting of the section 24 upon the head 21 of the wedge member causing the section 24 to be 40 self-centered or properly positioned relative to the stud screw and pin, this movement being effected by rotation of the rod 17 having its threaded portion 16 cooperating with the head 21. The pin 10 is shifted into the 45 pocket 3 for engaging the rear edge of the thread cutting blade 4 to vary the cutting edge 5 thereof with respect to the central opening in the die head, the blades 4 being retained in adjusted positions by the screws 50 28.

From the above detail description of the device, it is believed that the construction and operation thereof will at once be apparent, and while there is herein shown and 55 described the preferred embodiment of the present invention, it is nevertheless to be understood that minor changes may be made therein without departing from the spirit and scope of the invention as claimed.

60 What is claimed as new is:—

1. In a threading die of the type described, a die block, thread cutting blades carried by the block and extending into a central opening of the block, pins slidably carried by the block engaging the rear edges

of the blades and screw-operated wedge members engaging the pins to move the cutting edges of the blades into the block opening, each wedge member formed of interengaging wedge sections with the tapering end 70 of the inner wedge section engaging the adjacent pin.

2. In a threading die of the type described, a die block, thread cutting blades carried by the block and extending into a 75 central opening of the block, pins slidably carried by the block engaging the rear edges of the blades, screw-operated wedge members engaging the pins to move the cutting edges of the blades into the block opening, 80 and set screws carried by the block adapted to engage one side of the blades for holding the same in adjusted positions, each wedge member formed of interengaging wedge sections with the tapering end of the inner 85 wedge section engaging the adjacent pin.

3. In a threading die of the type described, a die block, thread cutting blades carried by the block and extending into a central opening of the block, pins slidably 90 carried by the block engaging the rear edges of the blades, screw-operated wedge members engaging the pins to move the cutting edges of the blades into the block opening, said block having openings therein, each 95 alined with a cutting blade with the rear end of the pin extending therein, an adjustable screw threaded in the block alined with the pin and extending into the opening and said wedge members moving between the 100 pins and screws for shifting the pins and cutting blades engaged by the pins.

4. In a threading die of the type described, a die block, thread cutting blades carried by the block and extending into a 105 central opening of the block, pins slidably carried by the block engaging the rear edges of the blades, screw-operated wedge members engaging the pins to move the cutting edges of the blades into the block opening, said block having openings therein, each 110 alined with a cutting blade with the rear end of the pin extending therein, an adjustable screw threaded in the block alined with the pin and extending into the opening and said wedge members being formed of relatively movable interengaging sections with the tapering ends of the wedge sections moving between the pins and screws and 115 screws carried by the block engaging the wedge members to cause the tapered ends thereof to shift the pin and cutting blades carried engaged thereby.

5. In a threading die of the type described, a die block, thread cutting blades carried by the block and extending into a central opening of the block, pins slidably carried by the block engaging the rear edges of the blade, screw-operated wedge members 125 engaging the pins to move the cutting edges 130

of the blades into the block opening, set screws carried by the block adapted to engage one side of the blades for holding the same in adjusted positions, said block having openings therein, each alined with a cutting blade with the rear end of the pin extending therein, an adjustable screw threaded in the block alined with the pin and extending into the opening and said 10 wedge members being formed of relatively

movable interengaging sections with the tapering ends of the wedge sections moving between the pins and screws and screws carried by the block engaging the wedge members to cause the tapered ends thereof to 15 shift the pins and cutting blades carried engaged thereby.

In testimony whereof I affix my signature.

STEPHEN SERA.
